WARE

METHOD OF AND APPARATUS FOR WINDING YARN

Application filed May 7, 1938. Serial No. 275,683.

This invention relates to method of and apparatus for winding yarns into desired packages, and relates more particularly to the winding of a multiplicity of parallel 5 yarns by applying a uniform tension to all the yarns that are being wound into the package.

An object of our invention is to provide means for winding a multiple end package 10 of yarn, which package is of larger size than has heretofore been possible.

A further object of our invention is to provide means for imposing a uniform tension on a multiplicity of yarns that are being led 15 to a winding device, whereby hard packages of yarns may be formed.

Another object of our invention is to provide means for applying a tension to yarns that are being wound, which means can be 20 applied to vary the tension and which may also be used for applying a modifying liquid to the yarns. Other objects of our invention will appear from the following detailed description.

25 The formation of multiple end packages of parallel wound yarns (i. e. yarns that are not twisted together prior to winding) has presented many difficulties, since if the tensions of the individual yarns are not the same, soft 30 packages are liable to be formed. As a result of this limitation, it has not been commercially feasible to form large packages of parallel wound yarn.

In accordance with our invention, we provide 35 a device for winding a multiplicity of yarns to a winding machine under uniform tension. This is done by causing all of the ends of the yarn to pass through exactly similar paths and thus be submitted to the same tension prior to being led to the winding device.

In one form of our invention, the yarns are led from their respective bobbins or other 45 packages arranged in a circle through balloon guides also arranged in a circle, and then through circularly arranged guides between circular discs mounted on a spindle. A multiplicity of such discs are employed and their 50 number may be varied in accordance with the tension desired. The yarns then pass be-

tween the discs and the spindle around guides to the winding devices, all under the same tension.

In order to further explain our invention, reference is had to the accompanying drawing 55 wherein:

Figure 1 is a vertical sectional view of the special yarn rack guide and tension device and also showing diagrammatically parts of a winding device.

Figure 2 is a plan view of a device and

Figure 3 is an enlarged vertical cross section showing the tensioning device in detail.

In accordance with our invention, we provide 60 a rack comprising the base portion 1 having the vertical standard 2. The base portion 1 supports the circumferentially arranged spindles 3 which are spaced equidistant from the standard 2 for holding the bobbins 4 of the yarns that are to be wound into 65 multiple end packages. Obviously instead of bobbins, other packages of yarns may be mounted on the spindle 3. The number of bobbins employed will vary with the number of ends required in the multiple end package.

The standard 2 supports a collar 5 in which are supported the arms 6, which have balloon guide eyes 7 at their extremity. The top of the standard 2 supports a concave plate 8 having special holes 9 in the outer edge thereof, which act as yarn guides for the individual ends. A polished steel spindle 10 is mounted on the top of the standard 2.

A plurality of washers 11, preferably of a soft material such as felt, are arranged about the spindle 10. If desired, a modifying liquid such as a conditioning, lubricating or softening liquid may be applied to the washers 11 for modifying the yarns passing between them as will later appear. This modifying liquid may be applied to the felt discs, either intermittently or in concentrated applications, to the uppermost washer, or by 90 properly arranged feeds to intermediate washers.

The frame of the winding machine is provided with guide rods 11^a for the yarn that is being passed to the winding mechanism. 10

The winding mechanism is provided with the winding spindle 12 and the traversing guide 13. The drawing shows a paper tube 14 for winding the multiple end cheese 15. Obviously packages other than cheeses, such as pirns, bobbins, cones, etc. may be wound if desired. The yarns to be wound are generally indicated as A.

The operation of the device is as follows: 10 Bobbins or other packages of yarns, equal in number to that desired in the cheese or other package to be wound, are mounted on the spindle 3 on the base 1 of the rack. The yarns are threaded through the balloon guide 15 7 and the orifices 9 in the concave plate 8, then between the same discs and are then caused to pass in the space between the walls of the holes of the upper felt washers 11 and the spindle 10. The friction due to the passage of the yarn between the felt washers 11 and also between the washers and the spindle 10 causes the required tension. By varying the number of discs used, the tension may be varied, as stated before. A conditioning 20 liquid of suitable character may be applied to the felt washers 11, which act as wicks for applying the same to the yarn A. The individual ends of yarns are then caused to pass in the form of a ribbon or band around the 25 guide rods 11^a to the traversing guide 13 onto the winding spindle 12. When rotation is applied to the winding spindle 14, the yarns are caused to balloon between the bobbins 4 and the balloon guide eyes 7 and pass between the washers and also in the space between the washers 11 and the spindle 10, and since each individual end of yarn follows exactly similar paths, the tension imposed thereon is the same for all. As a result, hard 30 packages such as cheeses of large size, may be wound, because of this uniform tension.

While this invention may be applied to the winding of yarns of all kinds, such as that of natural silk, cotton, reconstituted cellulose (rayon), it is particularly suitable for winding yarns made of or containing cellulose acetate or other organic derivatives of cellulose. Such organic derivatives of cellulose may be other organic esters of cellulose 40 such as cellulose formate, cellulose propionate, cellulose butyrate or cellulose ethers such as methyl cellulose, ethyl cellulose and benzyl cellulose.

It is to be understood that the foregoing 45 detailed description is merely given by way of illustration and that many variations may be made therein without departing from the spirit of this invention.

Having described our invention, what we 50 claim and desire to secure by Letters Patent is:

1. In means for winding multiple end packages, the combination of a common winding device with a yarn rack having circumferentially arranged means for mounting the

5 packages of the yarn to be unwound, individual guides for the ends of the yarn and felt washers arranged equi-distant from said means for mounting the packages, the plurality of ends of yarn passing between the same washers to the common winding device.

2. In means for winding multiple end packages, the combination of a common winding device with a yarn rack having circumferentially arranged means for mounting the 75 packages of the yarn to be unwound, individual guides for the ends of the yarn, a spindle and felt washers mounted on said spindle and arranged equi-distant from said means for mounting the packages, the plurality of ends 80 of yarn passing between the same washers to the common winding device.

3. In a method of winding a multiple end 85 yarn package the step of applying a uniform tension on the plurality of ends of yarn by causing the same to pass through precisely corresponding paths and in contact with precisely corresponding surfaces applying tension to a common winding device.

4. In a method of winding a multiple end 90 yarn package the step of applying uniform tension on the plurality of the ends of the 95 yarn by causing the same to pass through precisely corresponding paths and in contact with precisely corresponding surfaces applying tension and a lubricant to a common winding device.

5. The method of winding a multiple end 100 yarn package which comprises drawing a plurality of individual ends of yarn by precisely corresponding paths and in contact 105 with precisely corresponding surfaces applying tension at points equidistant from each of the said yarn sources.

6. In means for winding multiple end 105 yarn packages, the combination of a common winding device with a yarn rack having means for supporting a plurality of packages of 110 yarn and means for applying a uniform tension to the yarns, said means being arranged 115 and positioned to cause the plurality of yarns to pass through precisely corresponding paths in their passage from the packages to the common winding device.

7. In means for winding multiple end 115 yarn packages, the combination of a common winding device with a yarn rack having means for supporting a plurality of packages of 120 yarn and means for both lubricating and applying a uniform tension to the yarns, said means being arranged and positioned to cause the plurality of yarns to pass through precisely corresponding paths in their passage from the packages to the common winding device.

8. In means for winding multiple end 125 packages, the combination of a common winding device with a rack having means for mounting a plurality of packages of yarn to be wound, washers and means for guiding the plurality of yarns from the packages between 130

the same washers in their passage to the common winding device, said means being arranged and positioned to cause the plurality of yarns to pass through precisely corresponding paths in their passage from the 5 packages to the common winding device.

9. In means for winding multiple end yarn packages, the combination of a common winding device with a rack having means for mounting a plurality of packages of yarn to 10 be wound, felt washers and means for guiding the plurality of yarns from the packages between the same washers in their passage to the common winding device, said means being arranged and positioned to cause the plurality 15 of yarns to pass through precisely corresponding paths in their passage from the packages to the common winding device.

10. In means for winding multiple end 20 yarn packages, the combination of a common winding device with a yarn rack having circumferentially arranged means for mounting the packages of the yarn to be unwound, individual guides for the ends of the yarn and 25 felt washers carrying a lubricant arranged equidistant from said means for mounting the packages, the plurality of ends of yarn passing through precisely corresponding paths between the same washers to the common winding device.

30 11. In means for winding multiple end yarn packages, the combination of a common winding device with a yarn rack having a base portion, an upright standard 35 mounted on said portion, spindles for the packages from which the yarns are to be wound arranged on the base portion at equal intervals on the circumference of a circle with the upright standard at its centre, balloon guide arms mounted on said standard 40 having eyes spaced equidistant from said standard, a spindle mounted on said standard and a plurality of felt washers mounted on said last named spindle, whereby the yarns 45 pass through precisely corresponding paths and have uniform tension applied thereto.

In testimony whereof, we have hereunto subscribed our names.

FREDERICK J. WILLIAMS.
RUSSELL ROBINSON.
